UNITED STATES PATENT OFFICE.

HENRY M. HALL, OF PHILADELPHIA, PENNSYLVANIA, ASSIGNOR TO
THOMAS G. LOVEGROVE, OF SAME PLACE.

HANDLE FOR STEAM AND OTHER VALVES.

SPECIFICATION forming part of Letters Patent No. 290,575, dated December 18, 1883.

Application filed January 29, 1883. (No model.)

To all whom it may concern:

Be it known that I, HENRY M. HALL, a citizen of the United States, residing in the city and county of Philadelphia, State of Pennsylvania, have invented a new and useful Improvement in Handles for Steam and other Valves liable to be heated, which improvement is fully set forth in the following specification and accompanying drawings, in which—
10 Figure 1 is a top or plan view of a valve-handle embodying my invention. Fig. 2 is a section thereof in line x x , Fig. 1. Figs. 3 and 4 are side elevations of modifications.

Similar letters of reference indicate corresponding parts in the several figures.

My invention consists in providing the handle of a valve liable to be heated with means, substantially as hereinafter set forth, whereby in operating the valve the hand is guarded and 20 prevented from being burned.

Referring to the drawings. A represents the handle of a valve liable to be heated by steam or other hot fluid admitted to said valve, said handle being of the form of an annulus or 25 wheel. The periphery of the handle is grooved, as at a , and in the groove is fitted a band, B, of rubber—a poor conductor of heat—which firmly retains its position in the groove, and is of such width as to project outwardly 30 beyond the peripheral edge of the handle.

It will be seen that when the valve is to be opened or closed the hand of the operator is placed in contact with the band B, and the power exerted thereon is communicated to the 35 handle, whereby the latter is rotated, as usual.

It is well known that when the handle of a heated valve is grasped the palm of the hand is most liable to be burned, owing to the pressure of the same on the handle and its sensitiveness. This is avoided by the projecting portion of the band, which removes the palm from the metal of the handle, and, if properly grasped, may also remove the fingers therefrom, thus guiding the hand and preventing burning thereof, a better hold of the handle being 45 also obtained.

The groove a may be rectangular, round, or dovetailed in cross-section, and the band similarly shaped; or when stretched or sprung into the groove the contiguous portion may assume the shape of the groove.

For handles such as are shown in Figs. 3 and 4 the sides may be grooved longitudinally or transversely to receive one or more bands, and produce results similar to those hereinbefore stated.

Having thus described my invention, what I claim as new, and desire to secure by Letters Patent, is—

The handle of a valve, provided with a guard 6c consisting of a rubber band, which is fitted in a peripheral groove of the same, substantially as and for the purpose set forth.

HENRY M. HALL.
